UNITED STATES PATENT OFFICE.

PERRY G. GARDINER, OF NEW YORK, N. Y.

IMPROVED MACHINE FOR WASHING MINERALS, &c.

Specification forming part of Letters Patent No. 44,526, dated October 4, 1864.

To all whom it may concern:

Be it known that I, PERRY G. GARDINER, of the city, county, and State of New York, have invented certain new and useful Improvements in Machinery for Washing and Separating Mineral and other Substances; and I do hereby declare that the following is a full and exact description of my said invention and machinery, reference being had to the drawings accompanying and making part of this my specification.

My invention is based upon the relative specific gravities which the metals to be washed and separated bear to each other, and to the quartz or other earths in which they are contained, compared with water; and my machinery is adapted to the separating the metals after the ores which contain them have been reduced to fine powder by previous processes; and the invention and novelty consists in the construction and arrangement of a series of two or more cylinders placed at successively lower levels in reference to each other, connected by pipes, and through which cylinders and their connections are conducted and carried the pulverized ores or earths to be operated upon, in connection with a current of water flowing rapidly through the series, and which stream of water, together with the pulverized earths or ores, are accelerated, as well as kept in a state of agitation, so that the particles being separated, the relatively-lighter parts of the pulverized matter are carried off from cylinder to cylinder, leaving the heavier and metallic parts in the cylinders, so that the separation is accomplished in the cylinders in the order of the specific gravities of the metals respectively. Thus in ores containing a variety of metals—such as gold, silver, copper, or iron, (as is the case with the Colorado ores)—the separation would be, first, of the gold as the heaviest, next the silver, next the copper, and then the iron; but where the ores are more simple, and only one metal exists or greatly predominates, the process for separating is more simple and requires a series of only two cylinders, while in the other case a series of a greater number of cylinders would be required.

In the accompanying drawings, Figure I represents a vertical longitudinal section through the center of two cylinders (of a series) and of their connections, one of the cylinders, the up-

per one, being represented with the head in position, and showing also the supporting-standard of the axis of the shafts within the cylinder upon which the axis rotates. The other (lower) cylinder of the series is in section, and the standard or support of the shaft or axis is shown only in part. The frame or bed on which the cylinders and their connections rest is not in section, but is shown in side elevation. Fig. II is an end elevation of the frame or bed of the machinery. Fig. III is a vertical cross-section through the center of one of the cylinders and its axis or shaft, and of the parts supporting it, showing also the drums or pulleys attached to the shaft. Fig. IV is a side view or elevation of two of the arms revolving in the cylinders. Fig. V is a vertical cross-section of a funnel and pipe by which the water and pulverized ore are introduced into the first cylinder of the series.

In all the figures the same letters and numbers represent the same parts.

A is the frame or bed of the machinery, and it is constructed so that its upper part will have a declivity or incline of about twenty-five degrees. Upon this inclined frame, which is narrow and oblong, I arrange the cylinders B. These cylinders are hollow, and of narrow width in proportion to their diameters, as shown in the two Figs. I and III in longitudinal and transverse section. These cylinders are cast with flanges b, by which they are firmly secured to the bed-frame with bolts. One head of the cylinders should be made removable by being cast separate from the body of the cylinder, and provided with flanges through which pass bolts b', by which it is tightly held to the cylinder, so as to form a water-tight joint. The cylinders have openings into them and out of them in their peripheries, as herein next described, these openings corresponding to each other in all the series. There are two openings at the bottom or under side, as seen at 12. The opening 1 at the bottom of the cylinder is for admitting the water, and in the first or highest cylinder on the frame is connected with the pipe C and funnel C'.

2 is an opening in the bottom of the cylinder, and is provided with a nozzle or flange, b, and which is stopped or unstopped by the stopper b' fitted to it, and screwing into it by a male and female screw-thread.

In the upper part of the cylinders are two other openings, 3 4, 3 being directly on the top and 4 being a little lower on the side. 3 is provided with a stopper, b'' , fitted into the neck of the opening, as in 2. The object of this opening is for cleaning and washing out the cylinders.

Opening 4 is connected with a hollow pipe, D, which first rises above the level of the top of the first cylinder, and then turns and descends into the lower part of the next cylinder in the series, thus connecting the interior of the two cylinders together by a communication of a tube whose joints should be watertight. The cylinders are so arranged upon the frame or bed that the center of each cylinder will be on a level with the lowest part of the periphery of the cylinder immediately preceding and above it—in other words, a horizontal line drawn through the center of the cylinder of the series in the direction of their line of position will always touch the lowest portion of the cylinder next above it.

It should be observed that the line of discharge from the lowest or last cylinder of the series must always be higher than the top of the last cylinder, as shown at D', Fig. I, in order that only the lighter parts of the material operated upon may pass off out of the last cylinder.

Within each cylinder are four arms, E, at right angles to each other, fast to the axis or shaft G, supported on the standards or upright brackets g, fast to the bed or frame A. The arms are driven by a belt from a prime mover connected with the pulleys or drums H at one end of the axle or shaft of the first cylinder of the series, the other end of the axle or shaft having a drum, I, or pulley by which it is connected with and gives motion to a drum upon the shaft of the arms of the next cylinder in the series, and so on in succession, the speed of each successive shaft being reduced one-half from that of the preceding, the last moving slowly, all the shafts and arms rotating in the same direction, except that when there are more than two cylinders in the series I give in such case to the shaft and arms of the last or lowest cylinder a rotation opposite to that of the others, in order to prevent a too rapid flow and forcing of the water and other materials from the cylinder, and at the same time to give as much agitation as possible to the contents of the lowest cylinder. The arms E are not solid, but are made open, each arm in five parts, two on each side and one at the end, as shown in Fig. IV. Around the arms for about three-quarters their length, beginning from the extremity of the arms, I stretch the wire-cloth e, the object of which is to assist in disturbing and agitating the matter within the cylinders, and to cause a more perfect separation of the metallic and other particles, but not so as to entirely stop the flow of water through the arms and of the material which it carries with it into and out of the cylinders through the series.

Although but two of the series of cylinders are shown in the drawings, this represents the construction and operation of a series of any greater number of cylinders that may be required, all of them being constructed as here represented.

Having thus described the construction of my machinery, I now proceed to describe the manner of using and operating the same.

The ores having been thoroughly broken up and reduced to powder of the finest and most perfect pulverization, the dust is introduced into the upper cylinder of the series with the water through the funnel C' and pipe C. At the same time motion is given to the shafts and arms in the cylinders by means of the pulleys and belts. The dust and water become disturbed and agitated in the first cylinder by the rotation of the arms, so that all the materials in the first cylinder tend to take a position according to their relative specific gravity. The gold, being heaviest, is separated by falling to the bottom of the cylinder, where it remains, while the other parts, not so heavy, are carried by the operation of the revolving arms and the current of water over through the pipe D into the next cylinder, where a similar process and result are produced with the contents so carried into it from the first cylinder, and this is repeated through the series of cylinders until the whole of the metallic portions of dust are retained and separated in the cylinders. Everything in the dust not specifically heavier than fourteen times that of water will by the operation be carried through the cylinders and pipes, and finally discharged at the discharge-pipe D' of the last cylinder, leaving behind in the cylinders all the metallic portions of the dust, whether it be gold, silver, copper, iron, or other metal, thus performing the operation of a complete separator and throwing off the earthy matters and parts of the ores.

The speed to be given to the rotating arms must be varied somewhat according to the character of the ores pulverized.

This machinery may be used with or without mercury as an amalgam; but when mercury is used, and there are more than two cylinders in the series, it should be placed in the two last or lower series only. Inasmuch as the other higher cylinders of the series will retain only the heavier particles of the metals, they will produce a sufficient separation without the need of mercury.

When the operation is performed, so that all the earthy matters are carried off through the discharge-pipe of the lower cylinder, the apertures 2 in the bottom of the cylinders are opened and the contents of each cylinder are discharged into the trough underneath successively, one after another, beginning at the lowest, by means of a current of water and by turning the arms.

All parts of the machinery are of iron, excepting the brasses in the water-tight journal boxes of the shafts of the arms in the cylinders.

Having thus described my invention and machinery and the operation thereof, what I claim therein as my invention, and for which I desire Letters Patent, is—

The washing and separating the metallic parts of the pulverized dust of ores from each other and from the earthy matters by passing the dust through a series of two or more cylinders arranged upon descending levels connected by pipes, in connection with a stream of water passing through the whole series from a head or funnel above the level of the highest cylinder, the action of the water and the wash-

ing and separating being accelerated and assisted by the revolving arms within the cylinders, substantially as described, thereby separating the metallic parts of the dust in the cylinders successively from cylinder to cylinder, beginning with the highest, according to the specific gravity of the metal, the heaviest being first separated and deposited, and so on through the series.

P. G. GARDINER.
